UNITED STATES PATENT OFFICE.

STUART G. McALISTER, OF WASHINGTON, DISTRICT OF COLUMBIA, ASSIGNOR TO THE
T. H. SYMINGTON COMPANY, OF ROCHESTER, NEW YORK, A CORPORATION OF MAINE.

DRAFT-RIGGING.

1,213,924.

Specification of Letters Patent. Patented Jan. 30, 1917.

Application filed March 20, 1916. Serial No. 85,371.

To all whom it may concern:

Be it known that I, STUART G. McALISTER, a citizen of the United States, residing at Washington, in the District of Columbia, have invented certain new and useful Improvements in Draft-Rigging; and I do hereby declare the following to be a full, clear, and exact description of the invention, such as will enable others skilled in the art to which it appertains to make and use the same.

The invention relates to draft rigging for railway cars, and more particularly to that class of draft rigging in which the means for limiting the rearward movement of the cushioning mechanism is formed as a central stop, and in which the means for connecting the coupler to the cushioning mechanism is horizontally arranged.

To this end the main feature of my invention, generally stated, consists in providing coöperating means on the coupler connecting means and on the car underframe which are adapted to prevent the disconnection from the car of the coupler connecting means, should the cushioning mechanism break, fail, or be displaced from its position, to thereby maintain the coupler in coöperative relation to the car underframe.

The coöperating means on the coupler connecting means and on the car underframe are preferably so located and arranged with reference to each other that they prevent movement of the coupler connecting means beyond the normal predetermined amount, and thereby serve to transmit the load beyond the capacity of the cushioning mechanism to the car underframe directly through the coupler connecting means.

There are other features of the invention as will appear from a more detailed description of the invention taken in connection with the accompanying drawings chosen for the purpose of illustration.

Throughout the specification and drawings like numerals designate like parts.

Figure 1 is a side elevation of a draft rigging and a portion of the car underframe, one of the draft sills and the adjacent portion of the coupler connecting means being omitted. Fig. 2 is a top plan view of the construction, illustrated in Fig. 1, some of the parts being shown in section. Figs. 3 and 4 are detail cross-sections, taken, respec-

tively, on lines 3—3 and 4—4 of Fig. 2 looking in the direction indicated by the arrows. Fig. 5 is an elevation, showing one of the coupler connecting means, illustrated in Fig. 1, in normal position with reference to the adjacent sill, portions of the followers and coupler key being in section. Fig. 6 is a view similar to Fig. 2 showing, however, a slightly modified construction. Fig. 7 is a cross-section showing a preferred form of supporting means for the cushioning mechanism. Fig. 8 is a view similar to Fig. 5, showing the form of coupler connecting means illustrated in Fig. 6, and Fig. 9 is a view similar to Figs. 2 and 6, but showing a further modification.

Referring to the form illustrated in Figs. 1 to 5 inclusive, the draft sills are designated by the reference numeral 1, 2 is the coupler, 3, 3 are the coupler connecting means, which may be a pair of separable rearwardly extending members which are adapted to be slidably connected to the coupler 2 by means of the transversely extending coupler key 4, which passes through the slot 5 in the coupler 2, and through the elongated slots 6, 6 and 7, 7 in the members 3 and draft sills 1, respectively.

The numeral 8 designates the front follower, which may for convenience be formed as an H-shaped member, having upper and lower laterally projecting ears or lugs 9, 9 and 10, 10, respectively, thereby providing on opposite sides of the follower slots or openings 11, 11, adapted each to receive one of the members 3. The rear follower 12 is also preferably provided with upper and lower laterally projecting ears or lugs 13, 13 and 14, 14, and the members 3, 3 are also adapted to extend between the respective pairs of lugs 13, 14. The rear follower 12 may, for convenience, be provided, intermediate each pair of lugs 13 and 14, with a laterally projecting lug 15 which is adapted to enter an elongated slot 16 in the adjacent member 3.

To hold the front follower from movement under draft strains, vertically spaced stops 17, 17 may be provided on the cheek-plates 18, which are adapted to be connected to the vertical faces of the draft sills 1, 1. The forward ends of the members 3 are each adapted to pass between the stop shoulders 17, 17 of the adjacent cheek-plate.

Each cheek-plate is preferably provided to

the rear of the stop shoulders 17 and intermediate the same, with an outwardly extending lug or projection 19, the members 3, 3 being each provided with a slot 20 to receive the projection 19 of the corresponding cheek-plate. The rear follower 12 normally contacts with the forward face 22 of a centrally arranged stop-and tie casting 21. The stop casting 21 preferably comprises a horizontally disposed web portion 23, reinforced by longitudinally extending ribs or flanges 24, 25, and by lateral ribs or flanges 26, 27. Rivets or other suitable means passing through the flanges 24 and through the draft sills 1 serve to rigidly and firmly secure the stop casting 21 to the sills.

Each member 3 is preferably provided with shoulders, such as 28, 28, adapted to contact with the laterally projecting ears or lugs 13 and 14 provided on the rear follower, and each of the said members is further provided with an inturned shoulder 29 at the rear end thereof, said shoulders 29 being adapted to contact with the outwardly extending shoulders 30 formed on the vertical web 27 of the stop casting 21.

The numeral 31^a designates the cushioning mechanism which may be of any desired form, a well known type of combined spring and friction cushioning mechanism being shown by way of example.

The operation of this form of draft rigging is as follows: Under buffing movement the coupler moves rearwardly independent of the connecting means compressing the cushioning mechanism between the front follower 8 and the rear follower 12, the latter, of course, being held from rearward movement by the rear stop 21. Under forward or draft movement the coupler, owing to its key 4, pulls the coupler connecting means forwardly and owing to the engagement of the coupler connecting means with the rear follower 12 the cushioning mechanism is compressed against the forward follower 8 which then abuts against the stops of the cheek-plates 18. The projections 29 and the ends of the slots 20 of the coupler connection means and the forward ends of the slots 7 in the sills are so positioned with reference to stops 30 and 19 secured to the underframe and the forward edge of the coupler key 4 that they all come into action simultaneously to limit the forward movement of the coupler to thereby prevent damage to the cushioning mechanism and distributing the load to eight different points on the car underframe.

In the form illustrated in Figs. 6 and 8 the coupler connecting means is preferably formed as a pair of separate members 3^a which are each provided at their inner ends with inturned lugs 29^a adapted to engage, under extreme forward movement, co-acting shoulders 30^a on the stop casting 21^a. Each

of the members 3^a is further provided with an inwardly extending arm 31 adapted to engage the forward face of the stop 21^a and the rear face of the rear follower 12^a. In order to securely brace and strengthen the arms 31, a reinforcing web or flange 32 is provided, and the stops 30^a are each provided with an opening 33 to receive the flange 32.

The cheek-plates 18^a are each provided with forward spaced stop shoulders 17^a adapted to engage and prevent forward movement of the front follower 8^a, and each cheek-plate is further provided with spaced limiting stop shoulders 17^b adapted to limit the rearward movement of the front follower in buffing. As the followers 8^a and 12^a are rectangular and lie wholly between the vertical planes of the interior faces of the arms of the coupler connecting means, supporting plates such as 34 are employed to maintain the followers in position. These plates extend transversely of the draft rigging and are connected to the lower flanges of the draft sills 1. In this form of mechanism under buffing the final load is transmitted to the sills at five places, namely, by the key 4 to the inner ends of the slots 7, by the front follower 8^a to the limiting stops 17^b, and by the rear follower to the rear stop 21^a, while under draft the load beyond the normal capacity of the cushioning mechanism is transmitted at six different places to the sills by the coupler connecting means 3^a through the engagement of the shoulders 29^a and 30^a, by the front follower to the stop shoulders 17^b, and by the key 4 to the front ends of the slots 7.

In the form illustrated in Fig. 9 the coupler connecting means 3^b is preferably fashioned as a horizontal yoke 35 provided with rear connected members 36 adapted to engage the forward face of a stop-member 21^b. Rearwardly of member 36 and preferably in line with the arms of the yoke, there are provided rearwardly extending members 37 having inturned ends, to provide forwardly facing shoulders 29^b adapted under extreme forward movement of the yoke 35 to engage the co-operating stops 30^b on the stop casting 21^b.

In place of cheek-plates provided with vertical stop shoulders such as are shown in the other figures, I employ a key connected follower, such as is indicated at 8^c, and to strengthen the sills 1 to compensate for the openings formed therein to receive the ends of the coupler key 4, and the follower key 4^c, there are provided reinforcing members 17^b each having slots 7^b and 7^c adapted to register, respectively, with the slots 7 and 7^a provided in the sills 1. In this form of the device, whenever either the buffing or draft strains exceed the capacity of the draft gear, the keys 4 and 4^c come into con-

tact with the ends of the slots in the sills through which they pass. Upon application of excessive draft strains to the device, the inturned shoulders 29^b of the rear end of the yoke 35 engage the coating stops 30^b on the stop 21^b, so that draft strains beyond the normal capacity of the gear are directly transmitted by the yoke to the car underframe. In all buffing operations the rear follower 12^c is supported by the stop 21^b, the buffing force being transmitted to the latter through the rear end of the yoke. It will thus be seen that all strains beyond the capacity of the cushioning mechanism are distributed to the car underframe at a large number of points.

To support the cushioning mechanism and the coupler connecting means a special form of supporting plate 38 is preferably employed. This plate, shown clearly in Fig. 7, is provided intermediate its ends with a curved portion 39 adapted to receive the cushioning means, and intermediate the ends and adjacent the curved portion 39 there are provided further portions 40, 40 adapted to underlie and form a support for the arms, here indicated at 3, of the coupler connecting means. This form of supporting plate is illustrated in Figs. 1, 2, 7 and 9. In Fig. 6, owing to the use of the limiting stops 17^a and the supporting plates 34 a flat supporting plate 38^a is employed.

It is believed that the method by which the various forms of my device are assembled or disassembled will be obvious; it will be noted, however, in the forms shown in Figs. 1 and 6 that it is necessary to first remove the cushioning mechanism and the followers after which the arms of the coupler connecting means may be swung inwardly so as to clear the stop shoulders and then lowered from between the sills, while in the form illustrated in Fig. 9 it is only necessary to remove the two keys and the supporting plate 38 to permit the device to be taken down as a unit.

The many advantages of my invention it is believed will be apparent from the foregoing description.

50 What I claim and desire to secure by Letters Patent is:

1. In a draft rigging, the combination with the draft sills, of a coupler, a cushioning mechanism therefor, means extending rearwardly of the coupler and adapted to operatively connect the same to the said cushioning mechanism, and stationary means connected to the said sills and adapted to coöperate with the coupler connecting means to limit the forward movement of the same, the said connecting means being capable of a lateral movement to permit the removal thereof independently of the said limiting means.

65 2. In a draft rigging, the combination

with the draft sills, of cushioning mechanism, a stationary stop member connected to the said sills, a coupler, means for operatively connecting the said coupler and cushioning mechanism, the said stop being arranged rearwardly of the cushioning mechanism and being provided with lateral projections adapted to coöperate with the coupler connecting means to limit the forward movement of the same.

3. In a draft rigging, the combination with the draft sills, of a coupler, cushioning mechanism therefor, said cushioning mechanism including a follower adapted to engage the coupler, means extending rearwardly of the coupler and adapted to operatively connect the same to the cushioning mechanism, and means rigidly connected to the sills, in rear of the said follower, said means being adapted to coöperate with the coupler connecting means to limit the forward movement of the coupler.

4. In a draft rigging, the combination with the draft sills, of a coupler, a cushioning mechanism in rear of the said coupler, a stationary stop member adapted to form a forwardly facing abutment for the said cushioning mechanism, means operatively connecting said coupler and cushioning mechanism, said means being located at the vertical sides of the said cushioning mechanism, and said stop member and means on said stop adapted to prevent forward movement of said coupler beyond a predetermined amount.

5. In a draft rigging, the combination with spaced draft sills, of a stop rigidly connected thereto, and bridging the space therebetween, a coupler, a cushioning mechanism, horizontally arranged means extending rearwardly of the coupler and adapted to connect the coupler and cushioning means, the said stop extending rearwardly of the cushioning mechanism and being provided with laterally extending means adapted to engage the coupler connecting means to limit the forward movement thereof.

6. In a draft rigging, the combination with spaced draft sills, of a stop rigidly connected thereto, and bridging the space therebetween, a coupler, a cushioning mechanism, horizontally separable means extending rearwardly of the coupler and adapted to connect the coupler and cushioning means, the said stop extending rearwardly of the cushioning mechanism and being provided with means adapted to engage the coupler connecting means to limit the forward movement thereof.

7. In a draft rigging, the combination with the draft sills, of a combined stop and tie casting, said casting having a centrally arranged forwardly projecting por-

- tion of less width than the main body portion of the said stop and provided adjacent the outer end of the said projecting portion with laterally projecting shoulders.
5. The combination with a coupler, of cushioning mechanism, and a follower, said follower having slots in the side edges thereof, a projection on said follower in each slot intermediate the walls thereof, links connecting said coupler and follower, said links each being provided with a slot to engage one of the said projections and shoulders on the said links adapted to engage the follower above and below the said slots.
9. In a draft rigging, the combination with the draft sills, of cheek-plates connected to the adjacent faces of the said sills, each of said plates being provided with a pair of spaced stop shoulders and a lug, said lug being located in a plane intermediate the said stops, a coupler, cushioning mechanism, means connecting the cushioning mechanism and coupler said means including a pair of separable members arranged at the sides of said coupler, each of the said members being adapted to pass between the stop shoulders of the adjacent cheek-plate and provided with an opening 30 adapted to receive the said lug.
10. In a draft rigging, the combination with the draft sills, of cushioning mechanism, a stationary stop member, a coupler, means for operatively connecting said cou-

pler and cushioning mechanism, said connecting means and said stop member having overlapping portions, said portions being adapted to be engaged to limit the forward movement of said coupler.

11. In a draft rigging, the combination with the draft sills, of a cushioning mechanism, a stationary stop member connected to the sills, a coupler, links extending at the sides of said cushioning mechanism and adapted to operatively connect the same to the coupler, said links and said stop member being provided with portions which are adapted to engage and limit the forward movement of the said coupler, the said links being removable independently 50 of the said stop member.

12. In a draft rigging, the combination with the draft sills, a coupler, a cushioning mechanism, said cushioning mechanism including a follower, cheek plates connected 55 to the draft sills and each provided with an abutment against which the said follower may bear, a stationary stop member in rear of said cushioning mechanism, means for operatively connecting said cushioning mechanism and coupler, and co-operating means on said cheek plates, stop member and coupler connecting means to limit the forward movement of said coupler beyond a predetermined point. 65

In testimony whereof I affix my signature.

STUART G. McALISTER.
